UNITED STATES PATENT OFFICE.

BARTHEL ERBE, OF PITTSBURG, PENNSYLVANIA.

IMPROVEMENT IN REVERSIBLE KNOB-LATCHES.

Specification forming part of Letters Patent No. **141,430**, dated August 5, 1873; application filed June 12, 1873.

To all whom it may concern:

Be it known that I, BARTHEL ERBE, of Pittsburgh, in the county of Allegheny and State of Pennsylvania, have invented a new and useful Improvement in Locks; and I do hereby declare the following to be a full, clear, and exact description thereof, reference being had to the accompanying drawing forming a part of this specification, in which—

Figure 1 is a face view of my improved lock, the operative parts of the latch being shown by dotted lines; and Fig. 2 is a perspective view of the same illustrating the manner in which the bolt is freed, so as to be reversed.

Like letters of reference indicate like parts in each.

My improvement consists in a reversible latch-bolt case with a front edge-plate made in two parts, each part forming two adjacent sides of the bolt-hole, and one part sliding lengthwise of the bolt to permit of the reversal of the bolt, substantially as hereinafter described.

To enable others skilled in the art to make and use my invention, I will describe its construction and manner of operation.

The lock-case is divided into two parts, $a\ a^1$, the part a consisting of the face and the upper edge a^3 , and that portion of the front edge a^2 which is above or bounds the upper side of the bolt b . The parts $a\ a^1$ are secured together by means of a screw, d , which extends through the slot c . This slot is made for the purpose of allowing the part a to be slid back the extent of the slot upon the lower part a^1 , being just sufficient to allow the front edge of the part a to clear the square head of the bolt b . The bolt b is provided at its back end with a

round shank, b^1 , and with a head, b^2 . The shank b^1 lies in the follower g in the ordinary way, this lock being of a very usual construction. When it is desired to reverse the bolt b the upper face a is pushed back, as shown in Fig. 2, the extent of the slot. Then it will be seen that the square head of the bolt b is entirely free on two sides, and may be turned around with ease. When the bolt has been turned the face a is pushed forward to its proper position, as shown in Fig. 1, and the lock is put upon the door in the usual way by means of screws through the holes h . When the lock is put on a door the bolt cannot be reversed without removing it, because the attachment screws prevent the sliding of the face.

The great advantage of this construction is its simplicity. The only change that is necessary in the construction of the lock is to divide the lock-case in the manner described and shown, and to make the slot c instead of an ordinary screw-hole, such as has heretofore been made.

What I claim as my invention, and desire to secure by Letters Patent, is—

The front edge-plate a^2 made in two parts, each part furnishing two adjacent sides of the bolt-hole, and one part sliding lengthwise of the bolt to permit of the reversal of the bolt, substantially in the manner and for the purposes set forth.

In testimony whereof I, the said BARTHEL ERBE, have hereunto set my hand.

BARTHEL ERBE.
